UNITED STATES PATENT OFFICE.

WILLIAM LAWRENCE, OF NEW YORK, N. Y., ASSIGNOR TO THE LAWRENCE ELECTRIC COMPANY, OF SAME PLACE.

CLOSED-CONDUIT ELECTRIC RAILWAY.

SPECIFICATION forming part of Reissued Letters Patent No. 11,481, dated March 26, 1895.

Original No. 516,631, dated March 13, 1894. Application for reissue filed March 26, 1894. Serial No. 505,220.

To all whom it may concern:

Be it known that I, WILLIAM LAWRENCE, a citizen of the United States, residing at New York, in the county and State of New York, have invented a certain new and useful Closed Conduit for Electric Railways, of which the following is a specification.

My invention relates to improvements in underground electric power systems for cars and other vehicles, and consists, first, in forming what I please to term the working conductor or main feed wire in sections, the said sections having suitable insulating material between them to prevent the electric current from running from one section into the adjacent section; second, in supplying the said sections with electricity from a continuous live wire which is insulated and incased within a suitable tubing or its equivalent, and, third, in conveying the electricity from the said live wire into a suitable cut-out box from which it is delivered to the auxiliary wire as the car passes over the different sections. A suitable conveyer provided with grooved contact wheels is employed for conveying the current from the auxiliary wire to the current distributor of a car or other vehicle.

I will now proceed to describe my invention in detail, referring to the accompanying drawings, forming a part of this specification, and in which similar letters of reference indicate corresponding parts in all the figures.

Figure 1 is a longitudinal section of my invention showing the current conveyer in full lines and taken on a line xx of Fig. 2. Fig. 2 is a transverse section taken on line yy of Fig. 1. Fig. 3, is a side elevation in detail showing one form of securing the insulating material to the auxiliary wire.

40 A, indicates a suitable main wire or conductor which is insulated and incased within a suitable tubing A' , or its equivalent. In the example shown the wire A is located in or contiguous to an underground conduit A'' . The insulation A'' is broken at given points as seen at a in Fig. 1; and a wire a' is connected with said live wire and leads to the contact points a'' in a cut-out box B, the box B being shown within the conduit A'' . The mechanism contained in the cut-out box B consists of a weighted lever b preferably fulcrumed as at

b' , and having contact points b'' adapted to be brought into engagement with the contact a'' as in Fig. 1. Pivoted to the lever b is a vertical rod c upon the outer end of which is 55 a support d upon which is secured the sectional live wire C located within the conduit A'' . A suitable stuffing box g is provided at the upper end of box B around rod c .

The current conveyer D, which is connected 60 with a suitable current distributor on a car (not shown) bears by means of its grooved contact wheels e upon the sectional wire C, the contact wheels e in traveling along causing said wire to be slightly depressed, or moved 65 laterally or vertically; this movement of the wire giving a suitable movement to the contact b'' by means of the rod c , whereby connection is made between the main wire A and the sectional wire C at the contacts a'', b'' . 70 It will be seen by the drawings that the circuit is broken at the end of each section of the wire C, the several sections of wire C being connected by suitable insulation D' .

It will be understood that the main live 75 wire A is at all times thoroughly insulated, and that the auxiliary wire C only receives the current while the car is passing over a certain section, the current of electricity being confined at that time to that section, and while 80 the current conveyer D is actually in contact with that section. This arrangement affords security against the escape of the current from the main wire A, whereby danger of the current becoming grounded and passing to 85 the surface of the street is overcome.

By my invention only one section of wire C will be charged with electricity at one time, excepting momentarily while the conveyer is passing over the insulation D' and when its 90 forward contact wheel is alone upon the adjacent section of wire, when these two sections will both be charged with electricity. By the means just described I avoid the dangerous sparking which would ensue if only one 95 contact wheel were used, by the action of such single contact wheel passing from one section to the other. The conveyer D depresses only that section of the wire upon which it is bearing at any time, and as soon 100 as it has left such section, the same is returned to its normal position by means of the

weighted lever *b*, thereby breaking the circuit at *a*" *b*" of each section consecutively. The insulation between the different sections of the auxiliary wire is secured in place by 5 screws, rivets, bolts, or in any other suitable manner, the form shown in Fig. 3 being the one I prefer to use.

As it is evident that many changes in the construction and relative arrangement of 10 parts might be resorted to without departing from the spirit and scope of my invention, I would have it understood that I do not restrict myself to the particular construction and arrangement of parts shown and 15 described, but that I reserve the right to make such changes, and that

What I claim as new, and desire to secure by Letters Patent, is—

1. In a system of electric distribution, a 20 main conductor, a contact, a connection from the main conductor to the fixed part of said contact, a weighted lever carrying the movable part of the contact, a sectional working conductor, a rod connecting the moving conductor, a rod connecting the moving conductor with the weighted lever, and a water 25 tight casing inclosing the contacts and lever, substantially as set forth.

2. In an electric railway supply system, the 30 combination of an insulated conductor main, branch conductors leading therefrom, contacts connected therewith, vertically movable rods, independently movable contact points to co-operate with the ones first mentioned, the said rods united at their upper ends with 35 the service conductor, one rod being located near each end of every section, casings inclosing said contacts and located exterior to the conductor main, and communicating therewith only by the branch conductors, and provided with water tight joints through the 40 walls of which casings said rods pass, and means whereby the rods are elevated simultaneously with the movement of the contact points.

3. In an electric railway supply system, the 45 combination of an insulated conductor main, branch conductors leading therefrom, contacts connected therewith, vertically movable rods, independently movable contact points to co-operate with the ones first mentioned, the said rods united at their upper ends with 50 the service conductor, one rod being located near each end of every section, casings inclosing said contacts and located exterior to the conductor main, and communicating therewith only by the branch conductors, and provided with water tight joints through the walls of which casings said rods pass, and means whereby the rods are elevated simultaneously with the movement of the contact points.

near each end of every section, casings inclosing said contacts and located exterior to the conductor main, and communicating therewith only by the branch conductors, and provided with water tight joints, through the 55 walls of which casings said rods pass, and means whereby the rods are elevated simultaneously with the movement of the contact 60 points; a slotted conduit, and a motor car provided with collecting means.

4. In an electric railway supply system, the combination of an insulated conductor main, branch conductors leading therefrom, contacts connected therewith, vertically movable rods, independently movable contact points to 65 co-operate with the ones first mentioned, the said rods united at their upper ends with the service conductors and at their lower portions with levers connected with one set of said contacts, one rod being located near each end of each section, casings inclosing said contacts and located exterior to the conductor main and communicating therewith only by the 70 branch conductors, and means whereby the rods are elevated simultaneously with the movement of the contact points.

5. In an electric railway supply system, the combination of an insulated conductor main, 80 branch conductors leading therefrom, contacts connected therewith, vertically movable rods, independently movable contact points to co-operate with the ones first mentioned, the said rods united at their upper ends with 85 the service conductors and at their lower portions with levers connected with one set of said contacts, one rod being located near each end of each section, casings inclosing said contacts and located exterior to the conductor 90 main and communicating therewith only by the branch conductors, and means whereby the rods are elevated simultaneously with the movement of the contact points, a slotted conduit, and a motor car provided with 95 collecting means.

In testimony of the foregoing specification I do hereby sign the same, in the city and county and State of New York, this 17th day of March, A. D. 1894.

WILLIAM LAWRENCE.
